(57) **CLAIM**

The ornamental design for an impact driver, as shown and described.

DESCRIPTION

FIG. 1 is a right front perspective view of an impact driver showing my new design.

FIG. 2 is a left side view of the impact driver of FIG. 1.

FIG. 3 is a right side view of the impact driver of FIG. 1.

FIG. 4 is a front view of the impact driver of FIG. 1.

FIG. 5 is a rear view of the impact driver of FIG. 1.

FIG. 6 is a top view of the impact driver of FIG. 1; and, FIG. 7 is a bottom view of the impact driver of FIG. 1.

The broken lines and the areas within the broken lines form no part of the claimed ornamental design.
